UNITED STATES PATENT OFFICE.

HOWARD S. MITCHELL, OF HOMER, LOUISIANA.

FIRE EXTINGUISHER.

1,421,979.

Specification of Letters Patent. Patented July 4, 1922.

Application filed June 25, 1920. Serial No. 391,592.

To all whom it may concern:

Be it known that I, HOWARD S. MITCHELL, a citizen of United States, residing at Homer, in the parish of Claiborne and State 5 of Louisiana, have invented new and useful Improvements in Fire Extinguishers, of which the following is a specification.

This invention relates to fire extinguishers, and comprehends the provision of a 10 device of this character, which is primarily designed for use in conjunction with oil storage tanks or the like, having gas vents.

The invention embodies amongst other features a spring actuated valve which controls communication between the storage tank and the atmosphere through the gas vent, and means for normally holding the valve opened, the means being of the character to automatically release the valve in- 20 cident to the igniting of the gas by lightning or any other cause, thus permitting the valve to close and smother the flame.

The nature and advantages of the invention will be better understood when the following detail description is taken in connection with the accompanying drawings, the invention residing in the construction, combination and arrangement of parts as claimed.

30 In the drawings forming part of this application like numerals of reference indicate similar parts in the several views, and wherein:—

Figure 1 is a fragmentary view of a storage tank as showing the fire extinguisher associated therewith.

Figure 2 is a vertical sectional view taken through Figure 1 showing the valve in opened position.

40 Figure 3 is a similar view showing the closed position of the valve.

Figure 4 is a top plan view.

Figure 5 is a horizontal sectional view, through the device.

45 Figure 6 is an enlarged fragmentary view showing the inactive position of the keeper.

Figure 7 is an enlarged horizontal sectional view taken through the keeper and valve stem with the parts arranged in the 50 manner illustrated in Figure 1.

Figure 8 is a bottom plan view.

Referring to the drawings in detail, 10 indicates an oil storage tank or the like,

having a gas vent 11, the fire extinguisher forming the subject matter of this invention 55 being indicated generally at A.

The fire extinguisher embodies a cylindrical casing 12 which is open at both ends and exteriorly threaded as at 13 to accommodate itself to the gas vent of the tank 60 shown. This casing may be of any suitable dimensions and has secured to the inside thereof a ring 14 constituting a valve seat. The valve is indicated at 15 and is pivoted within the casing 12 immediately adjacent 65 the valve seat 14. As when in this specific instance, and clearly illustrated in Figure 7, the underside of the valve 15 has secured thereto a plate 17 having a hook like extremity 18 which is fitted about a pivot bolt 70 19 and is then suitably secured to the casing 12. While this provides for the pivotal movement of the valve, the valve may be mounted in any suitable manner for the same purpose. Rising from the opposite 75 side of the valve is a projection 20, the latter being bifurcated as shown and defining spaced lugs 21 between which the valve stem 22 is pivotally mounted. This valve stem is of substantially rectangular formation 80 throughout the major portion of its length, but is also provided with a cylindrical portion 22' which operates through an opening centrally of the hood 23, the latter constituting a guide for the valve stem. The hood 85 23 is supported upon the casing an appreciable distance above the upper end thereof, through the instrumentality of standards 24 which are terminally secured to the casing 12 in the hood in any suitable manner. En- 90 circling the cylindrical portion of the valve stem, is a coiled spring 25 which has one end bearing against the nut 26 associated with the said stem, the opposite end bearing against the hood 23. This spring 25 func- 95 tions to automatically move the valve to its closed position in a manner to be herein- after described. The valve stem 22 is also provided at a point in its length with an opening 27.

100 Secured to the inner side of the casing 12, is a metallic strap at 28, the latter being vertically disposed within the casing, and terminating to provide a portion arranged across the casing at one side and in close 105 proximity to the valve stem. This portion

29 is arranged at a right angle to the vertically disposed portion 28, and supports the chamber at 30 for the reception of an explosive. The portion 29 is also provided 5 with an opening 31 for the purpose to be presently described. Pivottally associated with the free extremity of the strap 28 is a keeper 32 which is movable toward and away from the valve stem, and when in active 10 position as shown in Figure 2 is arranged in parallelism with the portion 29 of the strap, and confining the valve stem 22 in the space between said parts. The keeper 32 is provided with an opening 33, in which is terminally fitted a pin 34 of any suitable material. The keeper 32 also carries a lug at 15 35 which is received within the chamber 30, forming a closure for the latter when the keeper is in active position.

20 In practice, the valve stem 22 is depressed against the tension of the spring 25, until the opening 27 of the stem is brought into horizontal alinement with the opening 31 of the said strap 28. With the parts thus 25 positioned, the valve is opened as shown in Figure 2, the valve being held opened when the keeper 32 is swung to an active position, positioning the pin 34 in said alined openings. Before setting the fire extinguisher 30 in the manner just stated, an explosive of any suitable character is positioned in the chamber 30. With the parts thus arranged, communication between the storage tank and the atmosphere is established through the 35 vent opening 11 of the tank, and should the gas escaping from the tank be ignited by lightning or in any other manner, the flame at the proper time would ignite the charge of explosive in the chamber 30, thereby forcing the keeper at 32 out of association with the valve stem, and allowing the spring 25 to automatically move the valve to a closed position. This obviously would smother the flame within the tank 10. Should for any 40 reason, the explosive charge fail to ignite, the flame would melt the retaining pin 34, which is made of fusible material, thus effecting a release of the valve stem from the keeper 32 and allowing the spring to function in the manner just stated. The hood 23 in addition to providing a guide for the valve stem, serves to confine the flame and the heat therefrom within the area of the explosive chamber at 30 and the pin 34 so 45 that these parts will be effected in quick order, with a resultant release of the valve stem and the closing of the valve.

50 Mounted upon the hood 23 is a bracket 36, and pivoted upon this bracket as at 37, is an indicator of angular formation. This indicator is shown at 38, and when the apparatus is set for use, the indicator assumes a horizontal position as shown. One end of the indicator overlies the adjacent end of the 55 valve stem, and when the valve moves from

its opened to its closed position, the indicator is caused to assume a vertical position as shown in Figure 3. By reason of the indicator, which can be readily determined at a distance from the tank whether the valve is 70 in its opened or closed position. The apparatus is not only simple in its constructiton, but is positive in its operation for the purpose intended.

75 While it is believed that from the foregoing description, the nature and advantages of the invention will be readily apparent, I desire to have it understood that I do not limit myself to the details herein shown and described, inasmuch as the same is merely 80 illustrative of the preferred embodiment of the invention, and that such changes may be resorted to when desired as fall within the scope of what is claimed.

85 What I claim is:

1. The combination with a storage tank having a vent opening, of an apparatus of the character described comprising a casing fitted in said opening, an annulus arranged within the casing and constituting a valve 90 seat, standards projecting from the casing, a hood supported by the standards above and in spaced relation to the casing, a normally opened valve arranged within the casing and including a valve stem slidably mounted 95 through an opening in said hood, explosive means for holding said valve opened and explosive means actuated at a predetermined temperature for effecting a release of the valve, and means for automatically closing 100 the valve subsequent to its release.

2. The combination with a storage tank having a vent opening, of an apparatus of the character described comprising a casing fitted in said opening, a normally opened 105 valve arranged within the casing and including a valve stem, means for holding said valve in opened posititon, a member arranged across the top of said casing an explosive chamber supported by said member 110 and adapted to receive an explosive charge, said means for holding the valve opened including a pivoted latch element adapted to be arranged in parallelism with said member, a lug carried by said element for closing the explosive chamber, said explosive being actuated to effect the release of said valve, and means for automatically closing 115 the valve subsequent to its release.

3. The combination with a storage tank 120 having a vent opening, of an apparatus of the character described comprising a casing fitted in said opening, a normally opened valve arranged within the casing and including a valve stem having an opening 125 therein, a member secured to the casing and extended across the top thereof, said member having an opening, an explosive chamber supported by said member and adapted to receive a charge of explosive, a pivoted 130

latch element associated with said member and adapted to be arranged in parallelism therewith, said element having an opening adapted to register with the aforementioned opening, a fusible pin adapted to be passed through said openings for holding the valve in an open position, a plug carried by said element for closing said explosive chamber, said explosive when ignited effecting the release of said valve, and means for automatically closing the valve subsequent to its release. 10

In testimony whereof I affix my signature.

HOWARD S. MITCHELL.
